OSCILLATORY APPARATUS

Stephen D. Laveie, Dayton, Ohio

Application August 5, 1941, Serial No. 495,520

12 Claims. (Cl. 250—36)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to high frequency oscillatory circuits and devices, and more particularly to methods and apparatus for the utilization of such circuits and devices in oscillation generators, especially for the purpose of producing oscillations having a high degree of frequency stability.

The methods and apparatus of this invention are particularly useful for operations in what are today termed the "ultra-high" frequency or "micro-wave" spectrums; for example, the range of frequencies above 50 megacycles per second; although it should be clearly understood that the utility of the invention is not limited to such frequencies.

One of the problems frequently encountered in high frequency electrical work is that of providing a high degree of frequency stability in apparatus such as oscillation generators, frequency determining resonance circuits, etc., and also of providing such apparatus with means for readily changing the operating frequency while maintaining high frequency stability. In operations on lower frequencies good frequency stability may be obtained by use of piezo-electric crystals, but for high frequency operation the use of such crystals is impractical because of the impracticability of producing a crystal having the extremely small dimensions which would be required. Of course, a crystal of practical dimensions can be used with harmonic generator or multi-vibrator apparatus, but such an arrangement is complicated, expensive, and bulky. Furthermore, even if some type of simple crystal control were practical, such apparatus does not permit easy variation of the operating frequency.

In accordance with my invention, by making the frequency determining portion of high frequency apparatus, such as an oscillation generator, for example, in the form of a heavy, mechanically rugged metal structure or housing having metal projections extending inwardly from opposite walls to form a lumped capacity element, and so dimensioned as to have a natural electrical resonance frequency equal to the desired operating frequency of the apparatus, I provide a structure which forms a high-Q resonance circuit of extremely high inherent frequency stability readily comparable to that obtainable with a piezo-electric crystal. Further, in accordance with my invention, means are pro-

vided to vary the relative positions of the internal projections so that the resonance frequency of the unit can be varied as desired. In oscillation generators embodying my invention, the oscillation generating elements are mounted inside of such a frequency determining unit so as to be suitably coupled to it, thus completely shielding the entire generator apparatus and eliminating all possibility of parasitic coupling with external circuit elements, shields, etc., which would detrimentally affect its efficiency and operating stability.

Accordingly, it is an object of this invention to provide high frequency apparatus of extreme frequency stability, and to provide means whereby the operating frequency of such apparatus may be easily adjusted throughout a relatively wide range.

It is a further object of this invention to provide such apparatus which is substantially self-contained and self-shielding, and which is simple, compact, and rugged, thereby being especially suitable for portable operation, as, for example, in aircraft or other mobile equipment.

Other objects will be in part obvious and in part pointed out hereinafter.

For further disclosure of the invention, reference may be had to the following description and to the accompanying drawings, showing one embodiment of the invention selected merely for purposes of illustration, in which:

Figure 1 is a horizontal section, taken on lines 1—1 of Figure 2, of an ultra-high frequency oscillator embodying the invention;

Figure 2 is a front plan view of the oscillator, partly broken away to show a portion of the control mechanism, taken in the direction of arrows 2—2 in Figure 1;

Figure 3 is a vertical section taken on line 3—3 of Figure 1;

Figure 4 is another vertical section taken on line 4—4 of Figures 1 and 3;

Figure 5 is an enlarged detailed section of the Lecher wire capacitive short-circuiting member taken on line 5—5 of Figures 1 and 3;

Figure 6 is a diagrammatic representation of the oscillator showing the electrical circuit; and

Figure 7 is a curve showing the tuning characteristics of the oscillator of Figure 1.

Referring to the drawings, the ultra-high frequency oscillator embodying my invention is entirely housed within a heavy, approximately rectangular, metal housing 2, preferably a one-piece aluminum casting of five sides having its sixth side closed by a heavy metal cover plate

4, suitably secured thereto as by means of the screws 6. The upper left-hand corner of the rear of this housing is cut away at 8 to provide an aperture in which an oscillator tube 10 is mounted and through which it is connected to the other elements of the oscillator within the housing 2. An additional shield portion 12 of heavy metal, preferably an aluminum casting shaped as shown in Figures 1 and 3, is provided to surround and shield the oscillator tube 10 and close the aperture 8, and is secured to the housing 2 by screws 14. This rugged, mechanically rigid housing 2, along with a variable lump capacity tuning element, hereinafter to be described, forms the primary frequency determining portion of the oscillator, and because of this rigid mechanical construction it imparts to the oscillator a high degree of frequency stability.

The vacuum tube 10 may be any suitable high vacuum tube capable, when connected in a properly designed circuit, of oscillating in the ultra-high frequency range. The particular vacuum tube 10, shown in the drawings, is of the "door knob" type having three elements—a plate, a control grid, and a filament—and is of the baseless variety in which the electrode supporting wires pass through glass seals in the envelope of the tube and act as the connector pins whereby the tube may be plugged into a suitable socket. In the present embodiment such a socket is formed by a right angle metal bracket or shelf 16 extending rearwardly from the back of the housing 2, as shown in Figures 1 and 3, and suitably secured thereto by screws and nuts 18. The central contact prong 20 of the tube 10, which is one of the filament connections, passes through a close-fitting hole 22 in the bracket 16 and presses against a spring terminal member 24 soldered, or in some other suitable manner secured to the underside of bracket 16 to form a contact between the filament prong 20 and the entire metal frame of the instrument, i. e., the housing 2. The other filament connection prong 20 passes through a large hole 23 in the bracket 16 and thence through a small close-fitting hole 30 in a metal plate 32 secured to the underside of bracket 16 by a suitable means such as the screws and nuts 33 but insulated therefrom by a strip of suitable low loss insulation material 34, such as that commonly known by the trade name "Amphenol," and presses a spring contact member 36 soldered or in any other suitable manner secured to the metal plate 32. With this arrangement the plate 32 and the bracket 16 act as a condenser connected across the filament terminals 20 and 26 of the vacuum tube 10 to by-pass any radio frequency currents which may appear on the filament terminal 26 to the terminal 20 which in turn is connected to what might be called "ground," i. e., the housing 2 of the oscillator.

The plate connection prong 33 and the grid connection prong 40 of a vacuum tube 10 are inserted into two spiral spring connector members 42 and 44, respectively, which, in turn, are connected to the ends of two parallel brass rods 46 and 48, respectively, which act as a pair of Lecher wires to form with the vacuum tube 10 a "long line" resonant circuit which, when suitably connected and energized, forms an oscillator circuit of the type frequently referred to as a "long line," "transmission line," or "90 degree line" oscillator. These rods 46 and 48 are so dimensioned that, including added length due to the effect of the elements of vacuum tube 10, they

have an effective electrical length which is slightly greater than one-quarter of the longest wavelength to which it is desired to tune the oscillator. Inasmuch, however, as the elements of vacuum tubes have considerable influence in the ultra-high frequency or micro-wave spectrums, the total physical length of the rods 46 and 48 is actually less than one-quarter of the longest wave-length. For example, in an actual oscillator of the construction shown in the drawings having a wave-length range of 44.4 to 60.0 centimeters, the rods 46 and 48 were about four inches long although one-quarter of the longest wavelength would be about 5.9 inches. The other ends of the rods 46 and 48 pass through and are rigidly secured to two supporting and guide blocks 50 and 52 formed of some suitable low loss insulation material, such as the above-mentioned transparent material commercially known by the trade name "Amphenol." These insulated mounting blocks 50 and 52 are in turn secured by screws 54 to a rectangularly-shaped metal bracket 56 (see Figures 3 and 4) attached to the cover plate 4 of the housing 2 by means of screws 58, as shown in Figure 3. This structure holds the rods 46 and 48 rigidly in fixed relation to each other so that the spiral spring contact members 42 and 44 are properly positioned with respect to the holes 22 and 30 in the tube supporting bracket 16 so that they are always in proper position to make contact with the contact prongs 20, 23, 33, and 40 of the tube 10 when cover plate 4 is secured to housing 2. As shown in Figure 4, two screws 60 and 62 are threaded through insulated blocks 50 and 52 and through the rods 46 and 48, respectively, to securely fasten the rods in the block 52 and to provide means for making electrical connections with the extremities of these rods. These rods 46 and 48 through screws 60 and 62 are connected by leads 64 and 66, respectively, to a pair of pin jacks 68 and 70 mounted on a metal cross member 72 extending between and secured to the upper sides 74 and 76 (see Figure 4) of the bracket 56, and insulated therefrom by insulation material 78. In a recess 80 in the housing 2, immediately above the pin jacks 68 and 70, two metal sleeves 82 and 84 are secured by screws 86. These sleeves partially shield and aid in the positioning of the pin-type plugs 86, shown only in Figure 4, used to connect the pin jacks 68 and 70 to external power circuits. Suitable capacities may be provided between the central pin members 88 of the plugs 86, if desired, thereby providing a by-pass to the "grounded" housing 2 for any unwanted radio frequency currents which may appear on the leads 64 and 66.

Tuning of the "long line" oscillator circuit is accomplished by positioning of a radio frequency short-circuiting member, generally indicated at 90, along the Lecher wires 46 and 48 to effectively terminate or "short" the "long lines" 46 and 48 by determining the zero potential or nodal point on these lines. Details of construction of this short-circuiting member 90 are shown in the enlarged cross-sectional view in Figure 5. Essentially the shorting member 90 is a condenser which, at ultra-high frequencies, offers a sufficiently low impedance to act as a suitable reflecting impedance at the nodal point of the Lecher wires. This condenser is formed of two flat plate-like members 92 and 94 having tubular projections 96 and 98 formed on their outer surfaces and having their flat faces separated by a strip of insulation material 100. The tubular

portions 96 and 98 snugly surround Lecher wire rods 46 and 48 so that the shorting member 90 may be slid along these rods to determine the frequency of the "long line" circuits thus formed. The plate-like members 82 and 84 are clamped together and secured to a driving member 102 by screws 104. The screws 104 are insulated from the members 82 and 84 and the driving member 102 by a sleeve of insulation material 106, and the driving member 102 is insulated from the plate member 82 by an inter-layer of insulation material 108.

To tune the Lecher wires 46 and 48 by sliding the shorting member 90 therealong, as above-mentioned, the driving member 102 is threaded to receive a partially threaded control shaft 110 extending parallel to the Lecher wires 46 and 48. This control shaft 110 is rotatably mounted in a bearing member 112 attached by screws 114 to the lower side of the insulated supporting block 50. A shaft 116 of insulation material, having a central recess 118 in one end thereof, is attached to the unthreaded end of the drive shaft 110 by means of a screw 120, as shown in Figure 3. The other end of this insulated shaft 116 is similarly secured by means of a screw 122 to one end of a gear shaft 124 which projects through the front cover plate 4 and is secured to a driving gear 126. Thus, the driving gear 126, rotated in a manner hereinafter to be described, rotates the threaded control shaft 110 to move the shorting bar 90 along the Lecher wires 46 and 48 toward and away from the plate and grid terminals 38 and 40 of the vacuum tube 10, thereby to adjust the natural frequency of the "long line" circuit formed by the Lecher wires 46 and 48 and the shorting member 90.

A variable lumped capacity structure generally indicated at 130, is mounted within the housing 2 between the rear wall thereof and the front cover plate 4. This variable capacity structure 130, in conjunction with the housing 2 and the cover plate 4, forms the principal frequency determining element of the oscillator from which the oscillator derives its high frequency stability. In the form shown in the embodiment of the invention herein described, this variable capacity element 130 comprises a plurality of concentric tubular members all having a common axis X—X extending from the back wall of the housing 2 to the cover plate 4. A first tubular member 132, provided with a flange portion 134, is secured to the rear wall of a housing 2 by screws 136 passing through this flange portion. The end of the tubular member 132 is cut on a predetermined curve at an angle with respect to the axis X—X, as, for example, in the embodiment shown, along the oblique line 138, as shown in Figure 1. This predetermined contour on the end of the tubular member 132 permits the variable capacity structure 130 to be given any desired capacity variation curve, whereby, as will be hereinafter described, its operation may be synchronized with the operation of other elements of the apparatus, as, for example, with the tuning of the Lecher wire structure by movement of the shorting member 90. Another cylindrical member 140, of inside diameter equal to the outside diameter of tubular member 132 and of uniform length, is rigidly secured to the outer end of member 132 as by means of a screw 142. On cover plate 4 opposite to members 132 and 140 and concentric therewith is mounted a third tubular member 144 provided with a flange portion 146 whereby it is secured by means of screws 148 to the cover

plate 4, as shown in Figure 1. Tubular member 144 has an inside diameter slightly less than the inside diameter of the opposing tubular member 132. A round piston-like plunger 150 is slidably mounted within the tubular member 144 so as to be adapted to slide toward and away from the tubular members 132 and 140 to vary the electrical capacity between the plunger 150 and member 132. The capacity between capacity member 140 and plunger 150 does not change. This ring member 140 is provided to act as a lump capacity element to determine the minimum lumped capacity of the resonance chamber and hence the highest frequency desired in the range of operation. Thus, changing the dimensions of capacity ring member 140 provides a convenient method for determining the frequency range of the oscillator. The sliding motion of plunger 150 is obtained by means of a rotatable threaded control shaft 152 meshed into a threaded axial hole 154 in the interior of the plunger 150. The threaded control shaft 152 is also threaded into one end of a collar 155 which in turn is secured to a gear shaft 156 by means of a screw 158. The gear shaft 156 passes through a suitable bearing hole in the cover plate 4 and is secured to an anti-backlash gear 160 by means of a set screw 162. A small pinion gear 164 is also attached to the outer end of shaft 156. A long helical spring 166, surrounding control shaft 152 and collar 155, is compressed between the back of the front cover plate 4 and the end wall of a recess 168 in the interior end of the plunger 150 to prevent backlash in the motion of the plunger 150 in response to rotation of control shaft 152. In order to prevent the plunger 150 from rotating within the tubular member 144, a slot 170 is cut along side of the plunger 150 parallel to the axis X—X, as shown in Figures 1 and 4, and a stud 172 is threaded through the wall of tubular member 144 to engage the slot 170.

The oscillator is coupled to the external circuits with which it is to be used by means of a concentric cable, illustrated schematically at 173 in Figure 6, which is attached to a concentric cable coupling device, generally indicated at 174, passing through one wall of the housing 2, as shown in Figure 1. This coupling member 174 comprises a threaded tubular sleeve 176 clamped in position in a hole in the wall of housing 2 by two threaded rings 178 and 180. A plug 182 of insulation material, such as the above-mentioned "Amphenol," is secured in the center of the tubular member 176 and a resilient metal prong receptacle 184 is positioned in the center of the insulated plug 182. This metal prong receptacle 184 is connected by a lead 186 to a tap 188 formed by a screw 190 threaded into the tubular member 132 at some predetermined position. Additional taps for varying the coupling of the concentric line 173 with the oscillator may be provided by additional screws, such as 192. A standard concentric cable may be connected to this coupling member 174 in the usual manner. Tuning of the oscillator shown throughout a wide frequency range is accomplished by simultaneously moving the short-circuiting member 90 along the Lecher wires 46 and 48 and moving the plunger 150 with respect to the fixed tubular members 132 and 140. The oscillator frequency increases as shorting member 90 moves toward vacuum tube 10 and as plunger 150 moves away from the tubular member 132. This simultaneous movement of the shorting member 90 and the plunger 150 is accomplished by providing

the threaded control shafts 110 and 152 with right-hand threads and by meshing the operating gears 126 and 160, connected respectively to the control shafts 110 and 152, as shown in Figure 2, so that gear 126 turns in a counterclockwise direction when gear 160 turns in a clockwise direction. As above-mentioned, gear 160 is of the anti-backlash type, having two symmetrical gear members 160 and 194 so assembled that gear 194 may rotate with respect to gear 160 which is firmly secured to gear shaft 155. Gear 194 is biased to rotate with respect to gear 160 by means of a tension spring 196, secured at one end to gear 160 and at the other to gear 194, so that the corresponding teeth in gears 160 and 194 tend to clamp the teeth of gear 126 under tension of spring 196, thus preventing backlash. The two gears 126 and 160 are rotated simultaneously by a control knob 198 attached to a shaft 199 journaled on the cover plate 4 and on a front panel 200 secured to the cover plate 4 by four screws 202 passing through four collars 204. The shaft 199 carries a pinion gear 206 which meshes with the antibacklash gear 160 as shown in Figure 2.

A calibrated dial 208, having gear teeth around its periphery, is mounted on a shaft 210 journaled in and extending between the cover plate 4 and the panel 200. It is so positioned that its gear teeth mesh with the pinion 164 mounted on the end of the gear shaft 155 attached to the variable capacity structure 133. A window-type aperture 212 is provided in the panel 200 through which the calibrated dial 208 may be viewed. The dial 208 may be suitably calibrated so as to indicate the frequency of the oscillator as the control shafts 110 and 152 are rotated by rotation of the control knob 198 to vary the frequency of the oscillator circuit elements.

The electrical circuit of the oscillator is shown diagrammatically in Figure 6. The housing 2, including the cover plate 4, is connected to ground. One filament terminal 20 of the vacuum tube 10 is connected to the housing 2, as above-described, which in turn is connected through a lead 220 to one side of a suitable source of current (not shown) for heating the filament. The other filament terminal 26 is connected to the other side of the filament heating source through lead 222 and also to the metal plate 22 which forms a capacity with a portion of the housing 2 so as to by-pass to ground any radio-frequency currents which appear in the filament circuit. The grid connection 40 of the vacuum tube 10 is connected to one end of rod 48, as above-described. The other end of rod 48 is connected, through the lead 66 and the pin pack 70, to a variable grid bias resistor 224, the other side of which resistor is connected through a suitable grid current meter 226 to ground. The plate connector 33 of vacuum tube 10 is connected to one end of the other Lecher wire or rod 46 and the other end of this rod is connected, through lead 64 and pin jack 62, to the positive terminal 228 of a source of high D. C. potential, not shown, the negative terminal of which is connected to ground. A suitable high potential A. C. might be used in place of D. C., if desired. As above-mentioned, suitable capacities may be provided at the pin jacks 63 and 70, by which the plate and grid leads pass through the housing 2, so as to provide a by-pass to ground for any unwanted high frequency currents which may appear on these leads beyond the shorting member 90. Thus, the portion of the rods 46 and 48 be-

tween the plate and grid of the vacuum tube 10 and the shorting condenser 90 act as Lecher wires, i. e., as a "long line" resonant circuit, to generally set the frequency of oscillation of the oscillator circuit, and the portion of these rods beyond the shorting condenser 90 merely act as connections to the plate supply 228, and to ground through the grid resistance 224. The "long line" oscillator thus formed is completely shielded by the housing 2 and the cover plate 4, and it is coupled to an ultra-high frequency resonator structure formed by housing 2, cover plate 4, and the variable lumped capacity structure 133. This latter structure, as above-described, forms the primary frequency-determining element of the entire oscillator and, being very rigid mechanically, one which has a degree of frequency stability comparable with that obtainable with a piezo-electric crystal. However, it has the decided advantage over a crystal-frequency control arrangement that, due to the provision of the variably positioned plunger 150, the fundamental resonance frequency of this resonator may be readily varied through a wide range of frequencies without materially altering its stability or efficiency.

As above-mentioned, the oscillator is coupled to external circuits with which it is to function through a concentric line 173, the outside shell of which is connected to the housing 2 through the threaded portion 176 of the coupling member 174 and the inter-conductor of which is connected through the receptacle 184 to a tap 188 on the tubular member 132 of the variable capacity element 133. The position of this tap may be varied to vary the coupling of the oscillator with external circuits. If desired, this coupling may be accomplished inductively by means of a loop or capacitively by means of a coupling plate instead of by means of the tap provided in the embodiment described. In this connection it should be noted that the smaller the coupling to outside circuits through concentric cable 173, the greater will be the stability of the oscillator, and by the same token, the smaller will be the power output of the oscillator. Thus, the amount of coupling to be used must be determined by the use to be made of the oscillator. The connection shown in Figures 1 and 6, in which the center conductor of cable 173 is connected to tap 188, provides fairly tight coupling to external circuits; whereas a connection to tap 192, or coupling by means of a capacity plate or an inductive loop would provide a considerably looser connection to external circuits and therefore greater frequency stability.

By means of the gear structure shown in Figure 2, with proper choice of the pitch of the threaded control shafts 110 and 152; size of the gears 126 and 160; dimensions of the Lecher wires 46 and 48, of the housing 2 and cover plate 4, of the variable capacity element 133; and shape of the curve 138 of the tubular element 132 of this structure, the movement of the shorting member 90 and the variable capacity plunger 150 may be so synchronized that the oscillator will oscillate with high frequency stability throughout a wide frequency range. This is illustrated by the curve shown in Figure 7, which is the tuning curve of such an oscillator in actual operation, showing the straight-line relationship between the position of the shorting condenser member 90, the position of the capacity plunger 150, and the oscillator wave-length in centimeters.

Thus, with an oscillator of the type described embodying my invention, ultra-high frequency oscillations of great stability can be generated without difficulty, even above 1000 megacycles, and the frequency of these oscillations can be varied at will throughout a wide range by simply turning the single control knob 198. Thus, the delicate adjustments through long control shafts and the need for tuning the filament circuit and other potential supply circuits, so necessary in oscillators of previously known types, are eliminated.

As many embodiments may be made in the above invention and as many changes may be made in the embodiment above described, it is to be understood that all matter hereinbefore set forth or shown in the accompanying drawings is to be interpreted as illustrative only and not in a limiting sense.

I claim:

1. A stable self-shielded, ultra-high frequency, high-capacity resonant circuit, comprising, in combination, a closed metal container, a first tubular metal member secured at one end to one wall of said container with its free end projecting inwardly therefrom, a second tubular metal member secured at one end to the approximately opposite wall of said container with its free end projecting inwardly therefrom toward and concentric with said first tubular member to form therewith an electrical capacity, at least one of said two tubular members being extensible to permit relative movement between the adjacent free end portions thereof, a third tubular metal member secured near the free end of said second tubular member and concentric with said first tubular member to form with said first member a fixed lumped electrical capacity, means for predeterminedly changing the resonance frequency of the high-capacity resonant circuit thus formed by said container and said three tubular members comprising means for relatively moving the free ends of said first and second members with respect to each other along their common longitudinal axis while maintaining a fixed electrical capacity between said third member and said first member, and coupling means positioned within said container for connecting said resonant circuit to an external electrical circuit.

2. A stable self-shielded, ultra-high frequency, high-capacity resonant circuit, comprising, in combination, a closed metal container, a first tubular metal member secured at one end to one wall of said container with its free end projecting inwardly therefrom, a second tubular metal member secured at one end to the approximately opposite wall of said container with its free end projecting inwardly therefrom toward and concentric with said first tubular member to form therewith an electrical capacity, the free end of one of said members being shaped to terminate in a plane oblique to the common axis of said members, at least one of said two tubular members being extensible to permit relative movement between the adjacent free end portions thereof, a third tubular metal member secured near the free end of said second tubular member and concentric with said first tubular member to form with said first member a fixed lumped electrical capacity, means for changing the resonance frequency of the high-capacity resonant circuit thus formed by said container and said three tubular members in a manner predetermined by the angle between said plane and said common axis comprising means for relatively

moving the free ends of said first and second members with respect to each other along their common longitudinal axis while maintaining a fixed electrical capacity between said third member and said first member, and coupling means positioned within said container for connecting said resonant circuit to an external electrical circuit.

3. A stable self-shielded ultra-high frequency oscillation generator, comprising, in combination, 10 a closed metal container, a tubular metal member secured at one end to one wall of said container with its free end projecting inwardly therefrom, an extensible cylindrical metal member secured 15 at one end to the approximately opposite wall concentrically with said tubular member with its free end projecting inwardly toward but out of physical contact with said tubular member to form an electrical capacity therebetween, a 20 threaded shaft meshed into a threaded hole along the longitudinal axis of said cylindrical member near the free end thereof, first control means for rotating said shaft to move the free end of said cylindrical member into and out of said tubular 25 member to vary the resonance frequency of the resonator formed by said container and said concentric members, a transmission line electron tube oscillation generator positioned within said container and coupled to said resonator to form 30 a stable oscillation producing unit, second control means for tuning said generator, manually operable means mounted on the outside of said container and operatively connected to said first and second control means for simultaneously 35 operating said control means to determine the oscillation frequency of the oscillation producing unit formed by said generator and said resonator, and coupling means positioned within said container for connecting said resonator to an external electrical circuit to be energized by said oscillation producing unit.

4. A source of ultra-high frequency oscillation, comprising, in combination, an ultra-high frequency resonator chamber, an electron tube mounted in said chamber, a ninety-degree transmission line connected to said electron tube and completely contained in said chamber to form a transmission line oscillator, and coupling means 45 coupled to said resonator for connecting said oscillator combined with said resonator to external electrical circuits as a source of oscillation.

5. In combination, an electron oscillator tube, a long-line oscillator circuit operatively connected to said tube, a metal housing enclosing said tube and circuit, said housing acting simultaneously as an element of a tuned circuit determining the oscillation frequency of said oscillator and to completely shield said oscillator.

6. An ultra-high frequency oscillation generator, comprising, in combination, a completely closed metal container, a metal projection extending inwardly from one wall of said container toward a portion of an approximately opposite wall thereof and forming an electrical capacity therebetween, first control means connected to said container to vary the distance between the end of said projection and said opposite wall portion, an electron tube mounted in said container, a pair of approximately parallel conductors directly connected to the elements of said tube and extending across the interior of said container to form with said tube a long-line ultra-high frequency oscillator circuit, a bridging member electrically connecting said parallel

conductors at any desired point along their length, second control means associated with said bridging member to vary its longitudinal position along said conductors, and operating means mounted on the outside of said container and connected with said first and second control means to simultaneously operate said control means to determine the oscillation frequency of said generator.

7. An ultra-high frequency oscillation generator, comprising, in combination, a completely closed metal container, a metal projection extending inwardly from one wall of said container toward a portion of an approximately opposite wall thereof and forming an electrical capacity therebetween, first control means connected to said container to vary the distance between the end of said projection and said opposite wall portion, an electron tube mounted in said container, a pair of approximately parallel conductors directly connected to the elements of said tube and extending across the interior of said container approximately parallel to the axis of said metal projection to form with said tube a long-line ultra-high frequency oscillator circuit, a bridging member electrically connecting said parallel conductors at any desired point along their length, second control means associated with said bridging member to vary its longitudinal position along said conductors, and operating means mounted on the outside of said container and connected with said first and second control means to simultaneously operate said control means to determine the oscillation frequency of said generator.

8. An ultra-high frequency oscillation generator, comprising, in combination, an electrical resonator comprising a metal container and an extensible metal projection connected to one wall of said container and extending across the interior thereof toward an approximately opposite wall portion, means for varying the extension of said projection toward and away from said wall portion to determine the resonance frequency of said resonator, a long-line type ultra-high frequency oscillator circuit including a vacuum tube mounted within said resonator, and means extending into said resonator for coupling said oscillator through said resonator to external electric circuits.

9. An ultra-high frequency oscillation generator, comprising, in combination, an electrical resonator comprising a metal container and an extensible metal projection connected to one wall of said container and extending across the interior thereof toward an approximately opposite wall portion; means for varying the extension of said projection toward and away from said wall portion to determine the resonance frequency of said resonator; a long-line type ultra-high frequency oscillator circuit mounted within said resonator and including a pair of parallel conductors, a capacitive element to bridge said conductors to determine the resonance frequency thereof, and a three-element vacuum tube having a grid connected to one of said conductors, an anode connected the other of said conductors and a cathode connected to said metal container;

and means extending into said resonator for coupling said oscillator through said resonator to external electric circuits.

10. An ultra-high frequency oscillation generator, comprising, in combination, an electrical resonator comprising a metal container and an extensible metal projection connected to one wall of said container and extending across the interior thereof toward an approximately opposite wall portion; first positioning means for varying the extension of said projection toward and away from said wall portion to determine the resonance frequency of said resonator; a long-line type ultra-high frequency oscillator circuit mounted within said resonator and including a pair of parallel conductors, a capacitive element to bridge said conductors and a three-element vacuum tube having a grid connected to one of said conductors, an anode connected to the other of said conductors, and a cathode connected to said metal container; second positioning means for moving said capacitive element to any predetermined point along said conductors; means extending into said resonator for coupling said oscillator through said resonator to external electric circuits; and frequency control means for simultaneously operating said first and second positioning means to determine the oscillation frequency of said oscillator.

11. A stable ultra-high frequency oscillation generator, comprising, in combination, an ultra-high frequency resonator chamber, means positioned therein for determining the resonance frequency of said chamber, an oscillator tube, electric resonant circuit means connected to said oscillator tube to form therewith a complete ultra-high frequency oscillator circuit, said resonant circuit means determining the oscillation frequency of said oscillator circuit, mounting means in said chamber for said oscillator tube and said resonant circuit means to position the oscillator formed thereby in electrically coupled relationship with said ultra-high frequency resonator, and means extending into said resonator chamber for coupling said resonator to external electric circuits.

12. A stable ultra-high frequency oscillation generator, comprising, in combination, an ultra-high frequency resonator chamber, first adjustable means positioned therein for determining the resonance frequency of said chamber, an oscillator tube, second adjustable electric resonant circuit means connected to said oscillator tube to form therewith a complete ultra-high frequency oscillator circuit, said resonant circuit means determining the oscillation frequency of said oscillator circuit, mounting means in said chamber for said oscillator tube and said resonant circuit means to position the oscillator formed thereby in electrically coupled relationship with said ultra-high frequency resonator, means extending into said resonator chamber for coupling said resonator to external electric circuits, and control means external to said chamber connected to said first and second adjustable means to adjust them simultaneously to tune said resonator and said oscillator circuit to substantially the same frequency.

STEPHEN D. LAVOIE.
